UNITED STATES PATENT OFFICE.

HANS USENER, OF KIEL, GERMANY, ASSIGNOR TO THE FIRM OF NEUFELDT & KUHNKE,
OF KIEL, GERMANY.

ARMORED DIVING DEVICE.

1,183,914.

Specification of Letters Patent.

Patented May 23, 1916.

Application filed July 24, 1915. Serial No. 41,805.

To all whom it may concern:

Be it known that I, Dr. HANS USENER, a citizen of the German Empire, residing at Kiel, in the Kingdom of Prussia, Germany, 5 have invented certain new and useful Improvements in Armored Diving Devices; and I do hereby declare the following to be a full, clear, and exact description of the invention, such as will enable others skilled 10 in the art to which it appertains to make and use the same.

In patent application No. 839769 a rigid container for rigid diving dresses having a variable gas charge for regulating the ascent 15 and descent is described, by means of which the diver can ascend and descend any suitable number of times. The interior of the container is in constant communication by means of a pipe with the surrounding water. The amount of gas contained is varied 20 by opening a compressed gas container or an exhaust valve for the gas inclosed in the container. By this arrangement the variations of the surrounding water pressure are 25 transferred to the charge of compressed gas, the volume of which is varied by suitable admission and discharge of water. The small variations in the uplift thereby caused may usually be disregarded, as the diver is generally provided with considerable controlling means of descent, in order to be able to 30 work with certainty. They may however, in certain cases, be appreciably deleterious where the diver, for example in working on 35 the sides of sunken ships or on a slimy or muddy bottom, must bring himself into an equipoise or fixed position or an approximate equipoise. But the diver finds himself in an unstable equipoise, in so far as when rising 40 beyond the position of equipoise, that is to say when the depth of water over the diver diminishes and there is a corresponding reduced pressure, the uplift constantly increases and forces the diver to the surface of 45 the water, while when descending beneath the position of equipoise it diminishes and forces the diver down. In this arrangement in which the interior of the container is in 50 constant communication with the external water, the diver is thus also not afforded the possibility of adjusting himself to a new position of equipoise.

This invention has for its object to overcome this disadvantage. This is obtained

by the insertion of a valve, tap, or other 55 suitable closing member in the pipe connecting the interior of the container with the surrounding water, which valve can be operated by the diver by hand. By this means the volume of gas contained in the 60 lifting body, and thus also the ascensional power may be kept constant and independent of the pressure.

Figure 1 is a central vertical sectional view of the diving dress and the rigid buoyant chamber, other parts being shown in elevation. Fig. 2 is a view showing the relation of the pressure reservoir and the buoyant chamber.

The rigid diving dress is shown provided 70 with a pressure reservoir *d* holding a supply of compressed air or the like. This tank is connected by means of a pipe *c* having therein a valve *e* to the rigid buoyant chamber *b* which passing between the legs is secured 75 to both the front and back of the body of the diving dress.

The chamber *b* is provided with a pipe *g* passing out near the upper part of the chamber and having its lower end near the bottom of the chamber. Passage of water through this pipe is controlled or closed by the valve *x* having a handle *x'* within the body of the diving dress in reach of the operator.

An exhaust valve *f* is provided for the buoyant chamber. The operation of the device is as follows:—The valves *f* and *x* are opened and water is allowed to enter the chamber *b* until only the desired amount of 90 buoyancy is produced, after which both valves *f* and *x* are closed. The buoyancy then remaining practically constant, even though the diver moves from one water level to another. If it is desired to increase the 95 buoyancy, valve *e* is opened and then valve *x* is opened slightly until the compressed air has expelled just enough water to produce the required buoyancy. If it be desired to decrease the buoyancy valves *f* and *x* are 100 opened until the water has forced out some of the air in the chamber.

The closing member may be connected by means of a common operating rod or a like means of transmission with the valve for admitting compressed gas from the compressed gas cylinder into the container, and with the valve for discharging gas from the

container, in such a way that it opens or closes itself in the same direction simultaneously with the operation of one of them.

I declare that what I claim is:—

- 5 1. A diving device comprising a rigid diving dress; a rigid buoyant chamber attached thereto and separated from communication with the interior thereof; a compressed air tank separate from the interior of the diving dress; a discharge pipe connecting the lower part of the interior of the chamber with the exterior; an exhaust pipe in the upper part of the chamber; a pipe connecting the interior of the tank with the interior 10 of the chamber; and valves in all of said pipes.
- 10 2. A diving device comprising a rigid diving dress; a rigid buoyant chamber attached thereto and separated from communication with the interior thereof, said chamber comprising one compartment; a compressed air tank separate from the interior of the diving dress; a discharge pipe connecting the lower part of the interior of

the chamber with the exterior; an exhaust 25 pipe in the upper part of the buoyant chamber; a pipe connecting the interior of the tank with the interior of the chamber; and valves in all of said pipes.

3. A diving device comprising a rigid 30 diving dress; a rigid buoyant chamber attached thereto and separated from communication with the interior thereof; and passing between the legs thereof; a compressed air tank separate from the interior of the 35 diving dress; a discharge pipe connecting the lower part of the interior of the chamber with the exterior; an exhaust pipe in the upper part of the chamber; a pipe connecting the interior of the tank with the interior of 40 the chamber; and valves in all of said pipes and operable from the interior of said dress.

In testimony whereof I affix my signature, in presence of two witnesses.

Dr. HANS USENER.
